UNITED STATES PATENT OFFICE.

IRWIN A. DEAN, OF NIAGARA FALLS, NEW YORK, ASSIGNOR OF ONE-HALF TO
FREDERICK N. C. JERAULD, OF NIAGARA FALLS, NEW YORK.

WINDOW-LOCKING DEVICE.

1,041,042.

Specification of Letters Patent.

Patented Oct. 15, 1912.

Application filed October 16, 1911. Serial No. 654,973.

To all whom it may concern:

Be it known that I, IRWIN A. DEAN, a subject of the King of Great Britain, residing at Niagara Falls, in the county of Niagara and State of New York, have invented 5 certain new and useful Improvements in Window-Locking Devices, of which the following is a specification.

My invention relates to a window-locking 10 device, which has for its object to lock both sashes in such a manner that they cannot be opened from the outside, even when, for purposes of ventilation the upper sash may be partly lowered.

15 The invention also relates to the particular means by which the upper sash is locked, and to the combination of parts whereby the movement of the lower sash causes or permits the operation of the locking mechanism which secures the upper sash in any one of its adjusted positions.

The preferred form of my invention is illustrated in the accompanying drawings, in which—

25 Figure 1 is an elevation, showing the upper and lower sash, and the relative position of the parts by means of which the raising of the lower sash releases the lock of the upper sash; Fig. 2 is a side elevation, 30 of the meeting portions of the upper and lower sash looking toward the right hand edge of the sashes; Fig. 3 is a horizontal section on the planes V—V' of Fig. 3; and Fig. 4 is a back view of the upper sash lock.

35 In order to permit the upper sash to be lowered for ventilation and yet be locked in its lowered position by the lower sash, I have devised the following arrangement. Mounted in the side jamb is a casing 22, 40 within which are levers z , z , pivoted at v , v . The inner ends of these levers have slots in which is a pin, normally pressed outward by a spring u . At their outer ends, these levers carry bolts α , α' , which extend outwardly through openings in the casing 22. One of these bolts α the unlocking bolt is arranged to project into the inclined groove of a casting, w , mounted at the upper portion of the lower sash, while for engagement 45 with the other bolt α' the locking bolt are provided a series of openings 23, in a socket plate t , set into the side rail of the upper sash. By raising the lower sash, the bolt α will slide along the tapered surface of the

50 casting w and cause the bolt α' to be with-

drawn from a socket 23; the upper sash can then be lowered to the desired extent, whereupon by lowering the lower sash to its normal position, the bolt α is free to move outwardly, permitting the bolt α' to engage in any one of the sockets 23, thus locking the upper sash against unauthorized movement, for the reason that it cannot be moved until the lower sash is raised, which cannot readily be accomplished. 60

65 I claim:

1. The combination with an upper sash having a series of openings therein, of a locking device located in the side jamb, said 70 slideable locking device comprising a locking bolt mounted on the end of a lever, a second slideable bolt mounted on the end of a lever, means for connecting the ends of the lever, a spring bearing against the connected ends of the levers and arranged to normally press 75 said bolts outwardly and a hollow casing having an internal wedge surface carried by the lower sash for operating the second bolt.

2. The combination with an upper sash having a series of openings therein, of a locking device located in the side jamb, said 80 locking device comprising a slideable locking bolt mounted on the end of a lever, a second slideable bolt mounted on the end of a second lever, means for connecting the ends of the 85 levers, a spring bearing against the connected ends of the levers, and means carried by the lower sash for operating the second bolt.

3. The combination of a window-frame and 90 sashes therein, an upper sash having a series of openings in the side thereof adapted to receive a slideable locking bolt, a locking device located in the jamb of the window-frame and adapted to coöperate with the 95 lower sash to unlock the upper sash, said locking device having slideable locking bolts mounted on levers and having corresponding inward and outward movements, an inclined compressing element attached to the 100 lower sash adapted to press one of the bolts on raising the sash and to release the bolt on lowering the sash.

4. The combination of a window-frame and sashes therein, an upper sash having a 105 series of openings in the side thereof and adapted to be locked by a slideable locking bolt engaging the openings, a locking device located in the jamb of the window-frame comprising slideable locking and unlocking 110

bolts mounted upon spring operated levers, and being normally projected outwardly, a lower sash having an inclined compressing element engaging the unlocking bolt and 5 adapted to compress the bolt on raising the sash and to release it on lowering the sash, said spring operated levers depressing the locking bolt upon the depression of the un-

locking bolt, and projecting the locking bolt upon the release of the unlocking bolt.

In testimony whereof I affix my signature in presence of two witnesses.

IRWIN A. DEAN.
